FOG GENERATOR

Harold A. Roselund, Toledo, Ohio, assignor to
 The De Vilbiss Company, Toledo, Ohio, a corporation of Ohio

Application February 10, 1944, Serial No. 522,193

1 Claim. (Cl. 252—359)

1

This invention relates to an apparatus for creating an artificial fog and particularly to such an apparatus which may be readily moved from place to place and does not require any outside source for operating power or for vaporizing heat.

In the type of apparatus involved, a comparatively non-volatile petroleum oil is ordinarily used as the fog material. This oil is passed through a heating unit where it is vaporized at a high temperature. Upon discharge into the atmosphere the vapor thus formed condenses into a persistent cloud of minute oil particles.

Such a fog generator is used primarily to conceal troop movements, fortifications and other landmarks or buildings which might be of interest from a military standpoint. In ordinary times, however, the apparatus, by creating a blanketing fog, may be of considerable value in combatting frosts in orchards and in depositing insecticidal ingredients upon vegetables, grains or other plants under cultivation.

The principal object of the invention is to provide a fog generating apparatus which is compact and which may be readily put into operation.

A further object is the provision of such an apparatus which will produce an artificial oil fog of high screening qualities.

Another object of the invention is the provision of a fog generator which is economical in the amounts of fog oil and fuel consumed.

Still another object is the provision of an apparatus which uses gasoline for creating heat and has means for rapidly and thoroughly absorbing the heat created.

Other objects and advantages of the invention will be apparent upon reading the following description with reference to the drawings.

The principal components of the generator assembly include supply tanks for fog oil, gasoline and water; pumps for the oil (with entrained water) and gasoline; a heating unit including a gasoline burner, combustion chamber, and oil coils; a blower for supplying combustion air to the gasoline burner; and a gasoline driven engine for driving the pumps and blower.

Among the features contributing to the various objects and advantages of the invention are the use of a single pump for delivering oil and water to the set of heating coils; of a single magneto for supplying the ignition spark to both the gas engine furnishing the operating power for the unit and the gasoline burner in the heating unit; an efficient gasoline burner adapted to this particular apparatus; a coil arrangement in the heating unit for efficiently transferring the heat

to the oil and water mixture passing therethrough; and a general arrangement of parts which brings them into a closely spaced but very cooperative working relation.

5 In the drawings:

Fig. 1 is a side elevation of a fog generator embodying the invention;

Fig. 2 is a combination side elevation and vertical section with parts broken away of the heating unit;

Fig. 3 is a vertical section of the gasoline burner;

Fig. 4 is a top view of the fog oil pump and water connections; and

Fig. 5 is an elevation of the discharge nozzles and nozzle manifold.

Referring more in detail to the drawings, particularly to Fig. 1, the apparatus as shown has a supporting base 1 on which is mounted a gasoline engine 2 and the heating unit 3. The gasoline engine 2 through its pulley 4 and belt 5 drives blower 6 and the fog oil pump 7. The pulley on the oil pump is indicated at 8 while the pulley on the blower is not shown.

25 The pump draws oil from supply drum 9 through insert pipe 10, connecting hose 11, valve 12 and then forces it through piping 13 into the heater 3 where it is connected to the coil 14 by elbow 15. The coil 14 has three sections, one

30 within the other, with the oil entering the outer section first and in turn passing through the middle section and the inner section. From the inner section the oil, which is now vaporized, enters upright pipe 16 which communicates with nozzle manifold 18 from which the oil vapor enters discharge nozzles 19. From the latter the vapor is discharged into the atmosphere where it is immediately condensed or precipitated into fog form. Gauge 20 shows the temperature of the oil

35 vapor within the manifold 18.

40 During its progress through the coil 14, the oil is progressively heated and finally volatilized from the combustion heat produced by gasoline burner 21. This burner is furnished gasoline

45 through supply piping 22. Gasoline is drawn from the storage tank 23 through tubing 24 by the pump 25 which is mounted on the side of the base of the engine 2 and is driven by an arm through the engine wall which is motivated by a cam on the main crank of the engine, details of

50 which are not shown.

55 Just above the pump 25 there is a T connection 26, fastened to tubing 24 to which a branch tubing 27 is connected for supplying gasoline to the carburetor 28 of the engine. Air reaches the

carburetor through air cleaner 29. Gravity flow from the tank 23 is sufficient to bring the gasoline to the carburetor.

The blower 6 drives air tangentially into annular space 30 surrounding the heating chamber. This air, after spiraling through space 30, passes upwardly to chamber 31 at the top of the heating unit and hence into the gasoline burner 21. This air furnishes oxygen for the burning of the gasoline. It passes down through the burner into the cylindrical combustion chamber 32, outwardly from the bottom end of chamber 32 with the gas residue of combustion, hence up between the sections of the coil 14 and out opening 33 into the atmosphere.

The air in traveling through space 30 around the heating chamber, cools the outer concentric walls of heating unit 3 and thus reduces the possibility of an operator being burned on contacting the outside surfaces; the preheating that is thus given the air contributes to efficient combustion and the conservation of thermal energy.

It has been determined that a certain amount of water flowing through with the fog oil improves the operation of the apparatus. The water and resultant steam minimize the formation of coke within the heater coils and also by their dampening effect, acts to prevent flaming or spontaneous combustion of the oil vapor as it is discharged into the atmosphere. Approximately one part of water to fourteen parts of oil has been found to be sufficient.

A water tank 34 is provided from which water passes through tubing 35 and 36 (see Fig. 4) into the inlet chamber of pump 7. Between tubing 35 and 36 is interposed a metering port member 37 with port cleaning needle 38 which is used occasionally to insure that the port does not become clogged. The needle is normally held away from the port by spring 39 and has an exterior button 40 by which it may be manually depressed.

There is a by-pass within the oil (and water) pump from its outlet to its inlet side which is controlled exteriorly through hand wheel valve 41. By manipulation of this valve the amount of oil and water passing to the heating unit may be controlled as its adjustment permits more or less oil and water to circulate through the by-pass.

The gauge 58, mounted on the side of heating unit 3, is connected through the wall of the unit with the coil 14 within. It shows the pressure of the oil passing through the coil and thereby indicates the flow rate as set by valve 41.

The water is mixed thoroughly into the oil through the agitation the two materials receive when passing through the pump. This dispersion of the water causes it to be more effective in preventing coke deposits and flaming at the nozzle than would be the case were it merely injected as a stream into the oil line by another pump or through the use of a Venturi injector.

From the magneto of the engine, which is mounted in a well known manner in association with the main shaft of the engine, extends cable 42 to the spark plug 43 of the engine. Another cable 44 also extends from the magneto. This enters housing 45a where it is clipped to the top of electrode 45 mounted in burner 21 for furnishing an igniting spark.

The gasoline reaching the burner through piping 22 enters annular chamber 46. From the chamber 46 a spaced series of nine downwardly extending ports 47 communicate with a second chamber 48. While in this chamber the

gasoline, after the unit is once started, is volatilized by heat passing through the walls of the burner from the combustion chamber below; and the gas vapor thus formed passes upwardly into extension 49 of chamber 48 and out of inwardly directed annular slot 50. Here the gasoline vapors are intermixed with the air entering the burner from chamber 31 above it, and this air after passing downwardly through large center opening 51 past the slot 50 continues into the reduced center 52 as well as into the series of passages 53 encircling the opening 52. The passages 53 are separated by spiral vanes or partitions 54 which give the air and gasoline vapor a whirling motion. The mixture of air and gasoline vapor ignites upon entering the combustion chamber 32.

When the generator is first put into operation there is no heat to volatilize the gasoline entering chamber 48 and a certain amount of it will pass downwardly in liquid form through bleeder passages 55 which are located in four or five of the vanes 54 and terminate above trough 56. The gasoline thus collected in trough 56 is ignited by sparks from the end 57 of the electrode 45 and the heat from this burning gasoline passing through the heater wall starts the volatilization of the gasoline in annular chamber 48. The resultant gas vapors are themselves ignited after passing through slot 50 and when combined with air they reach the region of flames arising from the trough 56. The gasoline initially arriving in trough 56 is quickly consumed and no more reaches it as the gasoline subsequently entering chamber 48 is vaporized before it has a chance of passing down through passages 55.

The amount of heat developed within the combustion chamber is well beyond that ordinarily obtained in a chamber of comparable size.

In securing this result the use of gasoline as a fuel is an important factor. Gasoline burns more rapidly than fuel oil and for this reason its rapid combustion in a chamber of fixed size may release considerably more heat than would be possible with another fuel.

The large volume of air delivered through the burner into the chamber is another contributing factor. It supplies the large quantity of oxygen required and carries the heat into contact with the coils. Then the flow of oil and water through the coils is at a high rate and this rapidly conveys away the heat created.

Because of the necessity for lightness in order to have the generator as portable as possible and because of the rough handling the unit is given during transportation, ordinary refractory materials for the walls of the combustion chamber are unsuitable. The use of a stainless steel shell takes care of these conditions. This withstands the high temperature needed to bring the oil and water to around 900° F. As other materials fail in one way or another for the purpose, stainless steel is also used for the tubing in the coils. Both for the combustion chamber and the coils a light gauge of this steel is entirely satisfactory because of its relatively high creep strength and resistance to corrosion at elevated temperatures. The use of such a gauge metal keeps the size and weight of these units down to a minimum.

For operating purposes the generator would ordinarily be set upon the ground at the site where the fog is to be created, but, however, may be operated upon the truck by which it is transported. Supplies of fog oil, gasoline, and water to replenish that previously placed in the tanks of

the apparatus may be brought along in extra drums.

When the supply tanks are all filled and it is desired to put the generator into operation the gasoline engine is first started. All valves are left in closed position until it is determined that the engine is operating satisfactorily and has reached its proper speed. The valve in the gasoline line 22 from the pump 25 to the burner is then opened. As soon as the gasoline becomes ignited and combustion is in progress water but not oil, is permitted to pass through the pump 7, and piping 13 into the coils. This flow of water keeps certain portions of the coils from overheating and the heat of the resultant steam passing out the nozzles 19 is recorded on gauge 20. It may thus be determined when the heating unit has reached its operating temperature. At this point the oil valve 12 is opened by swinging handle 12a and oil is drawn through the pump with a small proportion of water. If too much oil is delivered to the coils there will be insufficient heat to vaporize it properly and a certain amount will be wasted by being discharged into the atmosphere in the form of unvaporized drops. This condition may be corrected by opening by-pass valve 41 and allowing some of the oil to recirculate through the pump. Consequently less oil will travel to the coils.

When it is desired to stop the generation of the fog, the oil valve 12 is closed and the gasoline flow to the burner interrupted. The unit is otherwise kept in operation for several minutes, however, with the water alone passing through the pump and coils. This flow of water serves to clean any residue of oil out of the coils and also protects the coils from being overheated through absorption of the heat remaining in the combustion chamber.

The water supply is then shut off and the gaso-

line engine stopped. The driving connection between the engine and the blower and pumps results in the operation of the latter when and if the engine runs and their stopping when the engine is stopped.

Having thus described my invention, what I claim is new and desire to secure by United States Letters Patent is:

In a fog generator, a vaporizing chamber for fog liquid, coils within the chamber through which the liquid travels, a gasoline burner for providing heat in the chamber, a pump for delivering gasoline to the burner, a pump for delivering fog liquid to the coils, a blower for forcing combustion air to the burner, a gasoline engine for driving the gasoline pump, liquid pump and blower, a gasoline tank supplying gasoline to both the burner and the engine, a magneto operatively associated with the engine, and dual cable means for carrying an ignition spark to the burner and also to the combustion chamber of the engine from the magneto.

HAROLD A. ROSELUND.
